UNITED STATES PATENT OFFICE.

GEORGE M. FRENCH AND WILLIAM B. PAVEY, OF CHICAGO, ILLINOIS, ASSIGNEES TO ECONOMY ENGINEERING COMPANY, OF CHICAGO, ILLINOIS, A CORPORATION OF ILLINOIS.

APPARATUS FOR LOWERING ARTICLES.

1,411,337.

Specification of Letters Patent.

Patented Apr. 4, 1922.

Application filed November 20, 1918. Serial No. 263,281.

To all whom it may concern:

Be it known that we, GEORGE M. FRENCH, and WILLIAM B. PAVEY, citizens of the United States, residing at Chicago, in the 5 county of Cook and State of Illinois, have invented certain new and useful Improvements in Apparatus for Lowering Articles, of which the following is a specification.

The invention relates to an article lowering 10 apparatus the general purpose of which is to facilitate the operation of removing articles from an elevated position, such as a work bench, to a lower position, such as the floor at the side or end of the bench.

15 A more specific object of the invention is to provide a machine comprising a framework having a vertically movable support and means of advantageous construction for controlling the movements of the support.

20 In the accompanying drawings, wherein we have illustrated a preferred form of our invention, Figure 1 is a side elevation of an apparatus embodying the features of our invention. Fig. 2 is a front elevation of the 25 same. Fig. 3 is a vertical sectional view taken on line 3—3 of Fig. 1. Fig. 4 is a fragmentary vertical sectional view taken on line 4—4 of Fig. 3. Fig. 5 is a fragmentary transverse sectional view taken on line 5—5 30 of Fig. 3. Fig. 6 is a fragmentary sectional view taken on line 6—6 of Fig. 2.

The machine comprises generally a base 1 having an upright frame 2 for guiding a support 3 for vertical movement, an upright 35 frame 4 for guiding a counterweight 5, a pulley 6 for the support and counterweight cables, and brake mechanism 7 for controlling the movements of the support. *a* indicates one end of a bench top of the usual 40 height adjacent to which the machine is stationed, and *b* indicates a receptacle adapted to be removably mounted on the movable support 3 in position to receive, from the bench, articles to be stacked. The receptacle 45 *b* is shown as comprising two adjoining side walls *c* and *d* and a bottom *e*, and may be provided with suitable supporting legs *f*.

The base 1 and frame 2 may be of any preferred construction adapted to support and 50 guide the movable support 3. The base is adapted to rest upon the floor of the building and preferably is not secured thereto so that the apparatus is portable; and the support 3 may comprise an upright frame 8 having 55 at its lower end a pair of forwardly extend-

ing arms 9 secured at the opposite sides thereof. At its upper and lower ends the frame 8 is also provided upon each side with guide rollers 10 arranged to operate in ways 11 formed in the upright frame 2 (Fig. 5). 60 The support 3 is thus movable vertically, being guided in such movements by the upright frame 2.

The guiding frame 4 for the counterweight 5 is located rearwardly of the guide frame 2 65 for the movable support, suitable ways 12 being provided in the opposite sides of the frame for guiding the counterweight in its vertical movements. The counterweight may be of any preferred form. 70

Upon the upper end of the frame 2 the pulley 6 is mounted. To this end a pair of bearing brackets 13 and 14 are secured to the frame so as to support the opposite ends of a shaft 15 which carries the pulley. Said 75 pulley comprises a pair of grooved wheels 16 and 17 secured together and fixed upon the shaft. The wheels have secured thereto the upper ends of cables 18 and 19, as at 20 and 21, respectively, and the cables are 80 wound in opposite directions on their wheels. At its lower end the cable 18 is secured to a cross bar 22 of the load support, and the cable 19 at its lower end is fastened to the counterweight 5. The wheel 17 may be made 85 somewhat larger than the wheel 16, and one of the wheels of the pulley, herein the wheel 16, is spiral eccentric in form so that its effective radius varies in the rotation of the pulley. The cables are so arranged with 90 reference to the pulley that when the receptacle *b* is in its lowermost position, the cable 18 is unwound from its pulley 16 so that the effective radius thereof is of minimum length (Fig. 6) and the cable 19 is 95 wound one or more times around its wheel 17. The counterweight 5 is of sufficient mass to normally raise the empty receptacle from its lowermost position into receiving position adjacent the end of the bench top *a*, and when 100 the receptacle is in this position, the effective radius of the wheel 16 is substantially of maximum length, so that the counterbalancing effect of the counterweight is at its minimum. Accordingly, when articles are 105 removed by a workman from the bench top to the receptacle, it will be seen that the added weight of the articles upon the receptacle will overcome the tendency of the counterweight to raise the receptacle, and when a sufficient 110

110

quantity of articles has been placed upon the receptacle, it will descend if permitted to do so. In such descent of the receptacle, however, it will be seen that the effective radius 5 of the wheel 16 decreases in length in the rotation of the pulley so as to increase the counterbalancing effect of the counterweight. Thus, the gradual increase of the load is compensated for by the increasing 10 effectiveness of the counterweight, in the descent of the receptacle.

The brake mechanism 7 is provided to facilitate the maintenance of the load support in the desired positions. Such mechanism 15 comprises a brake disc 23 fixed on the shaft 15, a brake band 24 and a hand lever 25. Said lever is pivoted to a depending portion 20 of the bracket 14, as at 26 at or slightly above the operator's head within easy reach when standing at the bench, and the opposite ends of the brake band are pivoted to the lever as at 27 and 28. A spring 29 connected at one end to the lever and at its 25 other end to an arm 30 on the frame 2 serves to actuate the lever to normally tighten the brake band upon the disc 23; and spring means 31 of ordinary construction is mounted upon an upstanding portion 30 of the bracket 14 so as to withdraw the brake band from the upper periphery of the disc when the lever 25 is raised.

In the operation of the machine, the empty receptacle *b* is brought to position with its bottom *e* adjacent the end of the bench top 35 *a*, for the convenience of the operator in placing articles upon the receptacle, the receptacle being held in this position by the brake mechanism 7. When the pile of articles upon the receptacle has increased so as 40 to make it desirable to lower the receptacle for the convenience of the operator, it is only necessary that he operate the brake mechanism by raising the lever 25, the added weight of the articles upon the receptacle 45 being sufficient to cause it to settle when the brake mechanism is released. After the receptacle has descended sufficiently to bring the top of the pile of articles thereon substantially to the plane of the bench top, the 50 handle is released to permit the brake mechanism to prevent a further downward movement of the receptacle until it is desired by the operator. As the pulley 6 rotates in the descent of the receptacle, the counterbalancing effect of the counterweight gradually increasing so as to counterbalance the articles placed on the receptacle owing to the fact that the effective leverage of the cable 55 18 upon the pulley decreases during such descent of the receptacle. When the receptacle finally reaches its lowermost position, it may be removed from its position upon the supporting arms 9 and a new receptacle placed thereon. Thereupon, by releasing the 60 brake mechanism 7, the new receptacle will 65

be raised by the action of the counterweight until stopped by the application of the brake, the counterweight being of sufficient mass to slightly overbalance the receptacle 70 when empty.

It will be observed that by the use of a machine of the character set forth, the operation of removing articles from a work bench, or other similar operations, may be greatly facilitated. The construction of the 75 machine is very simple and moreover the machine is capable of quick and easy operation, requiring a minimum amount of attention from the operator.

We claim as our invention: 80

1. A work handling apparatus comprising, in combination, a horizontal base, an upright frame mounted on the base, a support guided by the frame for up and down movement and having a pair of forwardly extending arms rigid therewith, a receptacle to be removably supported upon said arms adapted to receive articles from an elevated position, and means for controlling the movements of the support and the receptacle 90 carried thereby comprising a counterweight, a pulley carried by the frame and operatively associated with said counterweight and said support, and brake mechanism normally holding said support against movement.

2. A portable work handling apparatus comprising, in combination, a base, an upright frame at one end of the base, a support 100 guided for vertical movement by said frame, a receptacle removably carried by said support and open at one side, and means for gradually lowering the receptacle from an elevated position so as to position it from time to time at convenient heights with respect to said elevated position for receiving additional articles by way of said open side, said means comprising a pulley, a counterweight, and means adapted to control the 105 operation of said counterweight.

3. An apparatus of the class described comprising, in combination with a bench top, a lowering apparatus comprising an upright frame positioned adjacent one end of said bench top and rising above the plane 115 thereof, a receptacle having an open side, a support guided for vertical movement by said frame and adapted to carry said receptacle with its open side adjacent the bench top, and means for controlling the 120 movements of said support and thereby of said receptacle comprising a counterweight, a pulley carried by the frame and operatively associated with said support and counterweight, and brake mechanism normally holding said pulley against rotation.

4. An apparatus of the class described comprising, in combination with a bench top, a lowering apparatus comprising an upright frame positioned adjacent one end of said 130

bench top and rising above the plane thereof, a receptacle having an open side, a support guided for vertical movement by said frame and adapted to carry said receptacle
5 with its open side adjacent the bench top, and means for controlling the movements of said support and thereby of said receptacle comprising a counterweight, a pulley carried by the frame and operatively associated with said support and counterweight, and brake mechanism normally holding said pulley against rotation, said brake mechanism including an operating arm extending forwardly over the bench top substantially to the forward edge thereof in convenient position to be grasped by an operator.

5. An apparatus of the character described comprising, in combination, a base, an upright frame at one end of the base, a support guided for vertical movement by

said frame, a receptacle for receiving articles from an adjacent elevation, said support having a pair of forwardly extending arms rigid therewith upon which said receptacle is adapted to be mounted, and controlling means for the support and receptacle comprising a counterweight, a pulley carried by the frame and operatively connected to said support and counterweight, and brake mechanism normally holding said support against movement whereby the receptacle may be positioned as desired relative to said bench top, said pulley being constructed so that the counterbalancing effect of the counterweight increases as the receptacle support descends.

In testimony whereof we have hereunto set our hands.

GEORGE M. FRENCH.
WM. B. PAVEY.
